UNITED STATES PATENT OFFICE.

CHARLES A. WARNER, OF NEW YORK, N. Y., ASSIGNOR TO ALBION L. WARNER, OF NEW YORK, N. Y.

SOFA OR CHAIR BEDSTEAD.

1,038,693.

Specification of Letters Patent. Patented Sept. 17, 1912.

Application filed May 12, 1911. Serial No. 626,806.

To all whom it may concern:

Be it known that I, CHARLES A. WARNER, citizen of the United States, and resident of New York, county of New York, and State of New York, have invented certain new and useful Improvements in Sofa or Chair Bedsteads, of which the following is a specification, reference being had to the accompanying drawing, forming a part thereof, in which similar letters of reference indicate corresponding parts.

This invention relates to convertible furniture of the sofa-bed and chair-bed variety; the object thereof being to provide an article of furniture of this character which in its initial, or folded form, takes up a small amount of lateral space in comparison with its width, which varies in accordance with the size of bed required; further objects being to produce furniture of the character named which is substantial, though light in weight, and so constructed that its parts may be readily disassembled and folded for purposes of moving; the several parts of the structure, when assembled, being maintained in proper relative arrangement necessary to alternately produce the two said articles of furniture.

The invention will be hereinafter fully described and specifically set forth in the annexed claims.

In the accompanying drawings forming part of this specification, Figure 1, is an end view of my improved article of furniture shown in the folded form of a chair; Fig. 2, a vertical sectional elevation; Fig. 3, a perspective view showing parts of the framework showing the device folded; Fig. 4, a sectional elevation of the device showing the parts in position forming a bed; Fig. 5, an inverted plan view; Fig. 6, a rear elevation; and Fig. 7, an end view showing one of the sides, or arms, removed.

In the example of my invention as shown by the drawing, I employ primarily a framework embodying a base A, comprising the horizontal beams 1 and lateral rails 2. Slidably mounted on the upper surface of the said base A, is a framework B, having a mattress supporting helical springs b, ranged over the upper surfaces of its horizontal beams 3, and rollers 4 on the bottoms of its end walls 5, said rollers bearing on the lateral rails 2 of the base A. Hinged to the framework B, by means of the three-

part hinges 6, is a seat-frame C, having hinged to its horizontally extended wall 7, an upholstered, spring-cushioned seat-frame D; said wall 7, also having folding legs 8, for supporting the frame C, when the device is used as a bed, as shown by Fig. 4, of the drawings.

Hinged to the end walls 5, of the frame B, by means of the three-part hinges 9, is a framework E, which embodies the end walls 10, and a connecting beam 11, having an upholstered and cushioned frame F, embodying a back when the device is used as a chair or sofa; this said frame F, is secured by means of the hinges f, whereby said frame may be readily swung into either of the positions shown respectively by Figs. 2 and 4 of the drawings. Folding legs 13, are pivoted to the frame E, for the purpose of supporting said frame when the device is used as a bed.

The seat of the device embodying the spring-cushioned frame D, which is hinged to the frame B, by means of hinges 12, normally occupies a position parallel with and extended over the framework B; but, when the device is used as a bed, said seat drops downwardly, and is held in suspended position by means of the chains 18, secured at their respective ends to the frames C and D.

Extended horizontally, when the device is used as a bed, between the end walls of the frames B, C and E, is a woven wire spring G, which is attached at one end to the horizontal beam 14, of the framework C, and at the other end to a slidable plate 15, which is mounted on bolts 16, said bolts extending respectively through said plate and the beam 11, of the frame E; said bolts each having an adjusting-nut 17, threaded thereto, whereby the spring G, may be stretched and maintained taut. On said spring G, a suitable mattress H, is supported, said mattress is shown in Fig. 4, of the drawings, partly in full and partly in dotted lines. The springs b, act as an auxiliary support for the mattress, and prevent sagging of the spring G and mattress H, when persons are reclining on said mattress, the device being used as a bed.

The parts above described are inclosed between end walls I, embodying arms for the chair or sofa; these are hinged to the lateral rails of the base A, and when in normal position engage a back board J, which

is provided with dowel pins *j*, for engaging openings in the sides *I*; the sides and back also being connected by means of hooks *i*, which engage pins *k*. The frame *E*, of the structure, is held between two swinging rods *L*, which are pivoted at their lower ends to fixed plates *19*, of the sides *I*, and at their upper ends to similar plates on the end walls of said frame *E*; thus the outward movement of the frame *E*, and its connected frames *B* and *C*, is limited and the rollers *4*, are prevented from leaving their rails *2*.

In the operation and use of the invention, when it is desired to convert the same from its initial chair or sofa-shape to a bed, it is simply necessary to swing the frame *C* into horizontal position, and then pull outwardly until the frames *C*, *B* and *E* are extended, as shown by Fig. 4 of the drawings; during this operation the seat frame *D*, automatically drops into position and the spring *G*, is stretched taut and on a horizontal plane, said spring being supported by and within said frames *C*, *B* and *E*, the end walls of said frames now forming side rails of a practically continuous frame for supporting the woven wire spring and its mattress; having set the supporting frame, the hinged part *F*, of the framework *E*, is swung backwardly to provide space for bed pillows. Or, if desirable, pillows may be placed at the opposite end—the bed in its extended form, as shown by Fig. 4, of the drawings, comprising a rectangular frame, which supports the woven wire spring in a manner permitting the use of either end as a head part. To reconvert the device into a sofa or chair, it is simply necessary to swing the frames back till they assume the positions illustrated by Fig. 2, of the drawings, at the same time folding the mattress and its supporting spring within said frames.

I have illustrated a narrow or single bed,

which embodies a chair, when folded, but it is obvious that by widening the structure sufficiently to form a double bed it becomes a sofa, when folded, instead of a chair.

Having thus described my invention, what I claim as new, and desire to secure by Letters Patent, is:—

1. In a folding bed, the combination, with three folding frames each embodying end walls and cross beams; of an elastic fabric supported by and between said frames and connected at its ends to the outer cross beams of the two end frames, and means comprising bolts and nuts for taking up slack in said fabric, and means embodying a base and end pieces for supporting and inclosing the said frames when folded, substantially as shown and described.

2. In a sofa or chair-bedstead, the combination, with three folding frames hinged to each other and each embodying end walls and cross beams, an elastic fabric supported by and between said frames and connected at its ends to the outer cross beams of the two end frames, the inner one of the two said end frames having a cushioned frame hinged thereto adapted for a back; and the outer one having a cushioned frame hinged thereto adapted for a seat; of a base, end pieces hinged thereto, a removable back-board, and swinging rods linking said end pieces to the inner one of the said end frames, whereby outward movement thereof is limited, substantially as shown and described.

In testimony that I claim the foregoing as my invention, I have signed my name in presence of two witnesses, this 10th day of May 1911.

CHARLES A. WARNER.
